ATTORNEY

UNITED STATES PATENT OFFICE.

MORTON B. SULTZER, OF NEW YORK, N. Y., ASSIGNOR TO HENRY J. RIVOIRE, OF NEW YORK, N. Y.

TOY PISTOL.

1,333,945.

Specification of Letters Patent. Patented Mar. 16, 1920.

Application filed August 7, 1919. Serial No. 315,822.

To all whom it may concern:

Be it known that I, MORTON B. SULTZER, a citizen of the United States, residing at New York city, in the county of New York and State of New York, have invented certain new and useful Improvements in Toy Pistols, of which the following is a specification.

My invention relates to a toy pistol designed for the projection of a boomerang device.

The object of my invention is to provide a simple toy by which a boomerang may be automatically projected to describe evolutions in the air similar to those of a boomerang projected manually by those skilled in the handling of weapons of this kind.

The projecting device is herein shown in the form of a pistol, but it will be obvious that this form has simply been arbitrarily selected and that any other embodiment may be used which will effectuate the purpose.

The invention is illustratively exemplified in the accompanying drawing, wherein Figure 1 is a plan view showing the boomerang in position; Fig. 2 is a side elevational view with parts broken away; Fig. 3 is a detail view of the actuating mechanism; and Fig. 4 is a fragmentary view showing the trigger and parts coöperating therewith.

Referring to the drawing in detail, 10 denotes the barrel of the piston and 10^a the handle thereof.

The barrel is longitudinally slotted at 11 in its upper face and is provided with longitudinal slots 12 in each of its lateral faces.

At the front of the barrel is a block 13 into which is extended one end of a rod 14 the opposite end of which bears in a second block 15 at the rear of the barrel.

Coiled about the rod 14 is an expansion spring 16, and mounted slidably on the rod 14 in advance of the forward end of the expansion spring 16 is a sleeve 17 having an upwardly projecting arm 18 and a downwardly projecting arm 19. The sleeve also has formed integrally therewith lateral wings 20 which extend through the slots 11 in the side walls of the barrel.

Pivoted near the rear end of the barrel is a trigger 21 having its upper face apertured as at 22 to act as a catch in engaging a notch 23 formed in the lower edge of the depending arm 19.

Secured to the barrel 10, preferably at one

side of its upper face, is a shelf or support 24, upon which the boomerang 25 is adapted to rest. The boomerang is triangular in shape, and when in position to be discharged has one of its arms extending across the upper face of the barrel in the path of the arm 18. Attached to the arm 18 is a cushion device 26 which may be in the form of a pad of leather, felt or other suitable material.

The trigger 21 is mounted on a spring 65 plate 27 which imparts a normal upward tendency to the trigger, the latter being movable about a pivot 28.

The operation of the device is simple, and may be briefly described as follows:—When the boomerang device has been placed in proper position (Fig. 1) on the shelf 24 the side wings 20 are engaged by two fingers and the sleeve 17 retracted until the notch 23 engages the aperture 22 in the trigger. In this position of the parts the spring 16 is strongly compressed. To discharge the device pressure is exerted on the trigger whereby the sleeve 17 is released from engagement with the trigger enabling the spring 16 to expand and forcibly project the sleeve and the parts carried thereby. As the cushion 26 strikes the arm of the boomerang in its path, such boomerang is thrown into the air and caused to describe the evolutions peculiar thereto.

What I claim is:—

1. A device of the character described, comprising a casing, a shelf carried by said casing and adapted to support a boomerang with an arm thereof extending transversely across such casing, and means in the casing for forcibly striking said arm and projecting the boomerang.

2. A device of the character described, comprising a barrel having a longitudinal slot therein, a shelf carried by said barrel and adapted to support a boomerang with an arm thereof lying across said slot, and boomerang projecting means movable in the barrel and having a projection traveling in said slot in position to strike the arm of the boomerang.

3. A device of the character described, comprising a barrel having a slot in its upper face and a slot in each of its lateral faces, a rod extending longitudinally within said barrel, a sleeve slidably on said rod, a coil spring compressible by retraction of said sleeve, an arm carried by said sleeve and pro-

jecting through the slot in the upper face of the barrel, side wings carried by the sleeve and projecting through the slots in the lateral faces of the barrel, a shelf carried by the barrel and adapted to support a boomerang with an arm thereof in the path of the arm projecting through the slot in the upper

face of the barrel, and a trigger adapted to engage and become disengaged from said sleeve.

In testimony whereof I have affixed my signature.

MORTON B. SULTZER.
